US0D1034073S

(12) **United States Design Patent** (10) Patent No.: **US D1,034,073 S**
(45) Date of Patent: ** Jul. 9, 2024

(54) **FLASK VAPORIZER**

(71) Applicant: **iVision Tech, Inc.**, Middletown, DE (US)

(72) Inventor: **Ali Kohbodi**, Irvine, CA (US)

(73) Assignee: **IVISION TECH, INC.**, Middletown, DE (US)

(**) Term: **15 Years**

(21) Appl. No.: **29/869,624**

(22) Filed: **Jan. 18, 2023**

(51) LOC (14) Cl. **07-01**

(52) U.S. Cl.

USPC **D7/507**; D27/162

(58) **Field of Classification Search**

USPC D7/507, 509-511, 523, 524, 530, 533, D7/536, 534, 537, 543, 300.1, 300.2, 303, D7/600, 619.1, 391, 392.1, 396.1, 396.2, D7/629, 900; D3/202; D9/503, 505, D9/435, 439, 531; D27/162; D24/110

CPC A63F 2009/0058; A47G 19/2205; A47G 21/18; A47J 41/00; B65D 1/00

See application file for complete search history.

(57) **CLAIM**

The ornamental design for a flask vaporizer, as shown and described.

DESCRIPTION

FIG. 1 is a top right perspective view.

FIG. 2 is a bottom left perspective view, the bottom right perspective view is a mirror image thereof.

FIG. 3 is a front view.

FIG. 4 is a rear view.

FIG. 5 is a left side view.

FIG. 6 is a right side view.

FIG. 7 is a top view; and,

FIG. 8 is a bottom view.

The portions of the flask vaporizer shown in broken lines form no part of the claimed design.

1 Claim, 8 Drawing Sheets
